UNITED STATES PATENT OFFICE

93,231

DESIGN FOR A PATROL TYPE OF FLYING BOAT

Isaac M. Laddon, Buffalo, N. Y., assignor to Consolidated Aircraft Corporation, a corporation of Delaware

Application October 12, 1933, Serial No. 49,464

Term of patent 3½ years

To all whom it may concern:

Be it known that I, ISAAC M. LADDON, a citizen of the United States, residing in Buffalo, in the county of Erie, and State of New York, have invented a new, original, and ornamental Design for a Patrol Type of Flying Boat, of which the following is a specification, reference being had to the accompanying drawings, forming part thereof:

Fig. 1 is a plan view of the patrol type of flying boat showing my new design;

Fig. 2 is a front elevation of the same as it would appear in flight; and

Fig. 3 is a side elevation of the patrol type of flying boat also as the same would appear while in flight.

Fig. 4 is a top perspective view of the flying boat; while

Fig. 5 is a bottom perspective view of the said flying boat as the same would appear in flight.

I claim:

The ornamental design for a patrol type of flying boat as shown.

In testimony whereof, I hereunto affix my signature.

ISAAC M. LADDON.
